Hollydale, Calif.

Application August 28, 1946, Serial No. 132,914

Term of patent 14 years

(Cl. D86—10)

To all whom it may concern:

Be it known that we, George A. Lemke and Eleanor L. Lemke, citizens of the United States, residing at Hollydale, in the county of Los Angeles and State of California, have invented a new, original, and ornamental Design for a Covered Combined Beauty Tray and Comb Holder, of which the following is a specification, reference being had to the accompanying drawing, forming part thereof.

In the drawing:

Figure 2 is a perspective view of the covered combined beauty tray and comb holder, the cover being removed; and

We claim:

The ornamental design for a covered combined beauty tray and comb holder, as shown.

GEORGE A. LEMKE.

ELEANOR L. LEMKE.
